UNITED STATES PATENT OFFICE

2,522,091

LIQUID HEATING APPARATUS

Maurel G. Burwell, Columbus, Ohio

Application May 5, 1947, Serial No. 745,904

1 Claim. (Cl. 122—14)

1
The present invention relates to hot water heaters, and more particularly to gas-fired hot water heaters of the type embodying a tank which receives water at relatively low temperatures and discharges water by convective flow at relatively elevated temperatures.

It is the general object of this invention to provide a liquid heating system which possesses improved heat-transferring qualities, and which more effectively and efficiently utilizes a given amount of heat to elevate the temperature of a body of water contained in an associated tank.

Another object of the present invention is to provide a liquid heating system embodying a pair of liquid-receiving tanks in which the liquid contained in each tank is efficiently heated by but a single fuel burner of a size and capacity of the type normally employed in heating the contents of a single tank.

These and additional objects and advantages will become readily apparent with a more thorough understanding of this invention, which may be derived from the following detailed description and the accompanying drawings wherein:

Fig. 1 is a longitudinal vertical sectional view taken through a hot water heating system formed in accordance with the present invention.

Fig. 2 is a side elevational view thereof;

Fig. 3 is a horizontal sectional view taken along a plane indicated by the line 3—3 of Fig. 1;

Fig. 4 is a vertical sectional view on a relatively enlarged scale disclosing the fuel burner and its associated flame port.

Referring now more particularly to the drawings, the present invention makes use of a substantially oval-shaped base 5 formed with an upstanding side wall 6, and an intermediately disposed substantially horizontal upper wall 7. The upper ends of the side wall 6 extend slightly above the upper wall 7 to provide a peripheral side flange. Resting upon the upper surface of the upper wall 7, are a pair of vertically arising water tanks 8 and 9 respectively. These tanks are identical in configuration, and possess a substantially circular cross sectional configuration. The lower portion of each of the tanks are provided with a circular flange 10 formed at the junction of the side and bottom walls of the tank, and it is upon this flange that each of the individual tanks are supported upon the base with the individual bottom walls of the tank disposed in vertically spaced relation to the upper wall of the base. The tanks are positioned in substantially longitudinal vertical alignment on the base

5, and are spaced from one another at their adjacent sides. Occupying the space between the two tanks is a vertically arising flue pipe 11 having its lower end fitted within and communicating with the open end of a passageway 12 formed in the upper wall of the base, and opening substantially beneath the tank 9. The upper end of the flue pipe 11 is provided with a laterally offset L-shaped stack 13 which extends exteriorly of the two tanks.

Extending inwardly of the base 5 through an opening formed in the side wall thereof, and disposed beneath the bottom of the tank 9, is a gas burner 14 which is provided with a plurality of flame orifices 15 substantially at its outer end. Supporting the outer end of the burner 14, and disposed directly above the flame orifices thereof is a rectangular flame port 16 which is supported by the upper wall 7 of the base and extends 20 downwardly through an opening formed therein. The flame port 16 is formed with spaced inner and outer walls 16a and 16b respectively, and one of the outer walls 16b is elongated in a downward direction to provide a supporting flange 17 for the end of the fuel burner 14. The space between the inner and outer walls of the flame port 16 provides a passageway through which atmospheric air may pass from beneath the base upwardly of the port and into a chamber formed 25 between the bottom of the tank 9 and the upper wall of the base, to insure complete combustion of any unburned fuel emanating from the fuel burner 14 within this chamber. Further the passageway between the inner and outer walls provides means whereby a draft is created at the burner 14 causing a flame issuing from the flame orifices 15 to be sucked upwardly through the flame port 16 into the chamber disposed below the bottom of the tank 9 and ultimately through 30 the passageway 12 and into the flue pipe 11. In view of the above relation between the burner 14 and the bottom of the tank 9, it will be seen that heat furnished by the burner 14 will be transferred directly to the bottom of the tank 9 and consequently to the liquid contained within the tank.

Disposed within the interior of the flue pipe 11, is a spirally wound and coiled conduit 18, similar to the side arm coil of the ordinary type hot water heater, in that the respective ends of the coil conduit are disposed within the upper and lower portion of the tank 8, in a manner affording communication with the interior thereof. The coil conduit 18 functions in the 55 normal manner of the side arm coil in that

heat applied thereto will be transmitted to the body of water contained within the coils, and will cause the water to circulate by convective flow upwardly into the upper region of the tank 8, and at the same time introducing relatively cool water into the bottom of the conduit. Heat is furnished to the coiled conduit 18 by means of the hot gaseous products of combustion emanating from the burner 14 and passing downwardly through the passageway 12 and ultimately within the flue pipe 11, thus affording a temperature transfer to the liquid contained within the tank 9.

The tank 8 is provided with a downwardly extending inlet conduit 19, which serves in the ordinary manner to supply liquid to the system substantially at the lower end of the first tank 8. The heated water present within the tank 8 at the upper end thereof is discharged through an interconnecting conduit 20 having one of its ends communicating with the upper portion of the tank 8, and having its other end extending downwardly through the tank 9 and opening substantially at the bottom thereof, whereby heated water present within the tank 8 is transferred to the lower portion of the tank 9. The discharge outlet of the entire system is disposed within the upper end of the tank 9 in the form of a conduit 21, and serves to furnish heated water to the hot water system of an associated house or building.

As shown particularly in Figs. 1 and 3 of the drawing, the entire outer surface of the tank 8 and 9 as well as the space surrounding the flue pipe 11 is provided with an insulating jacket 22 which serves to greatly reduce the heat loss within the associated system, and presents a neat and attractive appearance to the assembly.

In view of the foregoing, it will be seen that the present invention provides both a structurally simple and mechanically efficient means for effecting the transfer of heat from a given quantity of fuel to a relatively large body of liquid, and further provides apparatus which may be quickly and easily installed, utilizing component parts which are common to the present day hot water heating system.

While a preferred form of the present invention

has been disclosed in detail in the foregoing drawing and description, it will be manifest that various modifications are possible without departing from the scope of the following claim.

5 I claim:

Liquid heating apparatus comprising a base; a fuel burner carried in said base; a first vertically arranged liquid-receiving tank mounted on said base and having a bottom wall disposed in close vertically spaced relation to said fuel burner to directly receive heat emanating from said burner; a vertically arranged flue passage disposed adjacent said first tank and communicating with the space between said burner and the bottom of said first tank for conducting gaseous products of combustion emanating from said burner upwardly alongside of said first tank; a second vertically arranged liquid-receiving tank mounted on said base adjacent to said flue passage; a heat transfer conduit positioned within said flue passage and communicating at its respective ends with the upper and lower regions of said second tank for transferring heat from gaseous products of combustion conducted in said flue passage to liquid received in said second tank; means for introducing liquid to the lower region of said second tank; means connected between said tanks for conducting liquid from the upper region of said second tank to the lower region of said first tank; and means for discharging liquids from the upper region of said first tank.
